UNITED STATES PATENT OFFICE.

CHARLES F. MILLER, OF MOORE, PENNSYLVANIA, ASSIGNOR TO WESTINGHOUSE ELECTRIC & MANUFACTURING COMPANY, A CORPORATION OF PENNSYLVANIA.

LOWER RAM FOR STOKERS.

Application filed March 28, 1924. Serial No. 702,490.

This invention relates to underfeed furnaces employing an inclined elongated fuel retort, or multiples thereof, alternating with tuyères to supply air under pressure to the fuel bed and comprising a primary feeding mechanism for introducing fuel into the retort and a secondary fuel-feeding mechanism located within the retort for the distribution of fuel delivered to the retort. One of the objects of my invention is to provide in apparatus of the character designated a secondary fuel-feeding mechanism which shall under the operator's control distribute fuel to the fuel bed in variable directions and secure not only the desired forward movement of the fuel but also obtain the desired upward movement of the fuel bed to the end that the contour of the fuel overlying the underfeed grate may be varied to secure efficient combustion of fuel of different characteristics.

Other objects of my invention will be understood by reference to the detailed description which follows, and to the accompanying drawings, in which Fig. 1 is a view in longitudinal section throughout the retort of an underfeed stoker illustrating disposition of a preferred form of my secondary feeding mechanism within the retort; Fig. 2 is a view in section showing on an enlarged scale the construction of the secondary feeding mechanism of Fig. 1; Fig. 3 is a view in section of the upper adjustable pushing structure; Figs. 4 and 5 are views in transverse section of the adjustable pusher taken on lines IV-IV and V-V, respectively, of Fig. 3; Fig. 6 is a view in longitudinal section of the pushing structure on line VI-VI of Fig. 4; and Fig. 7 is a fragmentary view illustrating a modification of my invention.

Referring to the drawings for a more detailed description of my invention, I show at 10 an underfeed stoker having a retort 11 and a bank of tuyères 12 contiguous thereto. A primary ram 13 disposed within the ram box 14 is adapted to force fuel from the hopper 15 into the retort 11. Fuel discharge means in the form of dump grates

16 at the rear of the retort 11 and tuyères 12 50 may also be provided.

Within the retort 11 is disposed a secondary feeding mechanism or ram 20 which is adapted to reciprocate upon a bottom plate 21 of the retort. The ram 20, as 55 shown, forms the bottom of the retort for the major portion of its length.

The ram 20 comprises a plurality of stepped pusher structures 25, 26, 27, 28, and 29 which are secured to a base plate 30. As 60 illustrated, each of the pushing structures 26, 27, 28, 29 comprises an L-shaped member having the extremities of its legs bearing against the base 30 to form a stepped structure. A depending lug 31 is secured 65 to the base plate 30, the lower end of which is pivotally connected to one end of a drive rod 32. The other end of the rod 32 is connected to a suitable lever mechanism associated with the ram 13 in such manner that 70 the reciprocation of the ram 13 also imparts a reciprocatory movement to the ram 20.

The upper pushing structure 25 of the ram 20 is constructed to provide different fuel-feeding capacities. As shown more 75 clearly in Figs. 3, 4 and 5, the pusher structure 25 is pivotally mounted at the forward end of the base 30 by means of a cylindrical portion 35 which engages a cooperating groove 36 in the member 30. A bracket 38 80 is secured to the base member 30 by means of a bolt 39 and is provided with an upstanding portion 40 in a face of which are provided notches 41. The pusher 25 is provided with a depending flange 43 which is 85 provided near its base with a projection 44, adapted to engage the notches 41 of the upstanding portion 40 of the bracket 38. An opening extending parallel to the flange 43 is provided in the pusher 25 to permit it to 90 pass down over the upstanding portion 40 of the bracket 38 in the different positions assumed when the projection 44 engages a notch 41. The arrangement is such that the loosening of the outer nut of the bolt 95 46 permits the rear end of the pusher 25 to be raised or lowered for the purpose of changing the area of its effective pushing

face and to be secured at a desired height by the engagement of the projection 44 in a notch 41.

The operation of my novel fuel-feeding device is as follows: Fuel is forced by the ram 13 into the inlet portion of the retort 11 and from there distributed rearwardly and upwardly by means of the reciprocating ram 20. If it is desired to increase the thickness of the fuel bed at the forward end of the stoker the forward pusher member 25 is elevated so as to give it an increased fuel moving effect. By reason of the greater upward inclination of the top face 25, as well as by reason of the greater effective area of the vertically-disposed face, which moves more fuel rearward than can be conveyed by the rear pushers 26, 27. The fuel entering the retort is therefore forced upwardly over the tuyère banks 12 to a greater height than if the foremost pusher 25 were in a lower position. In this manner, by changing the relative position of the pusher 25 with respect to the base member 30, it is possible to control to a large extent the thickness of the fuel bed in the forward portion of the stoker, and, consequently, the thickness of the fuel bed in the subsequently traversed portions of the bed. The particular disposition of the pusher 25 that will secure the most efficient results depends largely upon the character of the fuel employed and to some extent upon other operating conditions.

In Fig. 7 I have shown a single wedge-shaped ram having a single pusher structure. This structure is in detail like that of the foremost pusher structure 25 of the ram 20 above described, and a detailed description thereof is deemed to be unnecessary. The secondary ram when constructed with but a single pusher operates in all substantial respects like the multiple pusher ram 20 above described and the operator is enabled to regulate the relative upward and rearward movements of the fuel by the adjustment of the angular relation and effective pushing area of the wedge-shaped pusher in the manner which has been fully described above.

While I have shown my invention in but two forms, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. In an underfeed stoker having an inclined retort, a ram in said retort comprising an adjustable pusher structure having

an effective pushing face, and means for changing the effective area of said face.

2. In an underfeed stoker having an inclined retort, a ram in said retort, comprising a pusher structure having a face transversely disposed to the direction of fuel movement, and means for changing the effective area of said face.

3. In an underfeed stoker having an inclined retort, a ram in said retort comprising a pusher structure having a face transversely disposed to the direction of fuel movement and means for adjusting said pusher structure to give said face different heights.

4. In an underfeed stoker having an inclined retort, a ram in said retort comprising a wedge-shaped pushing structure whose base constitutes a pushing face, and means for changing the angle of the wedge to give the pushing face different effective areas.

5. In an underfeed stoker having an inclined retort, a ram adapted to reciprocate along the retort bottom comprising a plurality of pusher structures, the uppermost of said pusher structures being adjustable to different fuel moving capacities with respect to the other pusher structures.

6. In an underfeed stoker having an inclined retort, a ram adapted to reciprocate along the retort bottom comprising a plurality of step-like pusher structures each having a vertically-disposed pushing face, one of said pusher structures being adjustable to give different effective areas to its pushing face.

7. In an underfeed stoker having an inclined retort, a reciprocable ram defining the major portion of the bottom of said inclined retort and comprising a plurality of pusher structures, the uppermost of said pusher structures being adjustable to different fuel moving capacities with respect to the other pusher structures.

8. In an underfeed stoker having an inclined retort, a reciprocable ram defining the major portion of the bottom of said inclined retort and comprising a plurality of step-like pusher structures each having a vertically-disposed pushing face, one of said pusher structures being adjustable to give different effective areas to its pushing face.

9. An auxiliary ram for underfeed stokers comprising a base member, a pivoted fuel supporting and pushing member carried solely by said base member, and means for securing said pivoted member in different angular positions with respect to said base member.

10. An auxiliary ram for underfeed stokers comprising a base member, a fuel pushing member, a bracket secured only to the base member, and means associated with the bracket for securing the fuel pushing

member in different positions with respect to the base member. associated with the bracket for securing the fuel pushing member in different angular 10 positions with respect to the base member.

11. An auxiliary ram for underfeed stokers comprising a base member, a fuel pushing member swinging from one end upon the base member, a bracket secured to the base member and supporting the other end of the fuel pushing member, and means

In testimony whereof, I have hereunto subscribed my name this 17th day of March 1924.

CHARLES F. MILLER.
